ATTORNEYS

UNITED STATES PATENT OFFICE.

ALBERT D. FIELD, OF WATERBURY, CONNECTICUT.

DESIGN FOR A BODY-PLATE FOR BUCKLES.

SPECIFICATION forming part of Design No. 27,688, dated September 28, 1897.

Application filed June 16, 1897. Serial No. 641,069. Term of patent 7 years.

To all whom it may concern:

Be it known that I, ALBERT D. FIELD, a citizen of the United States, residing at Waterbury, New Haven county, State of Connecticut, have invented and produced a new and original Design for Body-Plates for Buckles, of which the following is a specification.

The characteristic features of my design are essentially those represented in the accompanying drawings, wherein—

Figure 1 shows a bottom view of a body-plate for buckles embodying my design. Fig. 2 is a longitudinal sectional view of the same on the line 2 2 of Fig. 1.

In the drawings, A represents the main body-plate of a buckle, which is provided with one or more openings *a* for securing the buckle-

body in place. The body portion is slotted or divided, as at *b*, so as to provide a central tongue *c*. The arms *d*, at each side of the central tongue *c*, are each provided with a depressed portion or pocket *e*, struck up from the body of the arms. Each of these pockets is surrounded on three sides by the portion of the material constituting the arms and is open on the inner side or on that side next to the central tongue.

What I claim is—

The design for a body-plate for buckles, substantially as herein shown and described.

ALBERT D. FIELD.
